DRIP RECEPTACLE FOR ICE REFRIGERATORS

Donald F. Rose, Riverside, R. I., assignor of one-half to William P. Walkley, Providence, R. I.

Application October 5, 1937, Serial No. 167,369

3 Claims. (Cl. 62—31)

This invention relates to a drip receptacle for collecting water which occurs by the melting of the ice in a refrigerator; and it has for one of its objects to eliminate or substantially lessen the 5 clogging of the drain pipe and overflowing which comes therefrom.

Another object of the invention is to form a seal to prevent any circulation of warm air into the ice containing compartment of the refrigerator.

Another object of the invention is the provision of a device which may be built into the refrigerator adjacent the ice compartment or positioned beneath refrigerators which are now in use for 15 accomplishing substantially the same results.

A more specific object of the invention is the automatic flushing of the drip receptacle at times spaced by sufficiently short intervals to prevent the accumulation of any slime upon the parts 20 of the structure.

With these and other objects in view, the invention consists of certain novel features of construction, as will be more fully described, and particularly pointed out in the appended claims.

25 In the accompanying drawing:

Fig. 1 is a sectional view showing the receptacle of my invention built into a refrigerator;

Fig. 2 is a perspective view of the device alone;

30 Fig. 3 is a sectional view of the device alone; Fig. 4 is a perspective view of the siphon conduit;

Fig. 5 illustrates the use of the invention below such refrigerators as are already in use.

In the use of ice refrigerators a certain amount 35 of slime is known to collect in the drain pipes which conduct away the melted ice. Food odors are known to dissolve in the water of the ice as the air circulates in the refrigerator and comes in contact with the water which has just melted 40 from the ice and is spread out over the surface of the ice. An appreciable amount of this dissolved material settles out of the water upon standing or upon evaporation and collects rather rapidly in the usual refrigerator drain pipes so as 45 to clog these pipes to such an extent that an overflow occurs, such collection of deposit frequently first occurs at the container which receives the drip to maintain an amount of standing water sufficient to serve as a means for sealing 50 the drain pipe of the refrigerator against air circulating through the pipe into the ice compartment; and in order to prevent the long standing of any water but provide for intermittent flows of a substantial volume through the pipe 55 at the time of any flow, I have provided an ar-

angement so that the water as it is drained from the ice compartment collects until a certain amount is accumulated and then when such amount is accumulated a flushing occurs by which substantially all of the water is drained from the receptacle in a flow of substantial volume from the receptacle, with this flushing occurring at such frequent intervals that no deposit will occur; and the following is a more detailed description of the present embodiment of this invention, illustrating the preferred means by which these advantageous results may be accomplished:

With reference to the drawing, 10 designates a refrigerator having a food compartment 11 and an ice compartment 12. The support for the ice 15 or that portion 13 upon which the water collects is inclined so as to discharge the water which melts from the ice 14 through opening 16 in the partition 13 which ordinarily exists as a drain pipe extending out of the refrigerator.

This invention, however, provides a receptacle 17 having side walls 18 and a bottom wall 19, which bottom wall is inclined toward a low point 20 at substantially the middle of the receptacle so that the first liquid which drops into the 25 receptacle will be conveyed to this low point 20. The side walls are rolled over at their top edges 21 and this receptacle may engage the partition 13.

A conduit of a cross-section wide in one dimension but narrow in another direction is bent into generally U-shape, as shown in the drawing, with the two legs of the U conduit 22 and 23 vertically disposed and of a height dependent on the frequency desired for flushing but necessarily below the top of side wall 18 and connected by the horizontal portion 25. The leg 23 is positioned closely adjacent to the bottom wall 19 at the low point 20 with a space 24 existent between its end and the bottom wall, while the 40 leg 22 is secured to the bottom wall to support the conduit in position. An opening 26 in the bottom wall registers with the opening in the conduit 22, while a drain pipe 27 is detachably secured to the collar 28 about this opening 26 to 45 conduct away the accumulation of liquid in the receptacle. These two portions of the conduit 22 and 23 of the same height are connected by a horizontal portion 25 which is broadened out laterally and in a horizontal direction and also 50 is narrow in a vertical dimension so as to provide a broad but wide connecting area. The area of any cross-section, however, of this connecting portion 25 is substantially the same as the area of the cross-section of the tube 22. The periph- 55

quick disbursement of the cold drop less condensation occurs on the outside of the receptacle which is detrimental in that this condensation collects to dampen or wet the parts about it or upon which it rests. 5

The foregoing description is directed solely towards the construction illustrated, but I desire it to be understood that I reserve the privilege of resorting to all the mechanical changes to which the device is susceptible, the invention 10 being defined and limited only by the terms of the appended claims.

I claim:

1. An ice box drip receptacle comprising a container having a bottom and side walls for 15 accumulating drip water from ice, a vertical outlet conduit extending through a wall of said container and to a height above the inner surface of the bottom wall thereof, a second upwardly extending conduit opening to said container closely adjacent the inner surface of the bottom wall, and means providing a passage connecting the bores of said conduits and of such 20 formation that a drop by drop filling of the container will eventually cause a syphonic flow of 25 the water from the container through the outlet conduit.

2. An ice box drip receptacle comprising a container having a bottom and side walls for 30 accumulating drip water from ice, a vertical outlet conduit extending through the bottom of said container and above the inner surface of the bottom wall thereof, a second upwardly extending conduit opening to said container closely adjacent the inner surface of the bottom wall, 35 and means within the container providing a passage connecting the bores of said conduits and of such a cross-section and area that a drop by drop filling of the container will eventually cause a syphonic flow of the water from the container 40 through the outlet conduit.

3. An ice box drip receptacle comprising a container having a bottom and side walls for accumulating drip water from ice, means for providing a low point in said bottom wall, a vertical 45 outlet conduit extending through the bottom of said container and above the inner surface of the bottom wall thereof but of a height less than the side walls, a second vertically extending conduit extending to substantially the same height 50 as said first conduit and opening to said container closely adjacent the inner surface of the bottom wall at the lower point thereof, and means providing a passage connecting the bores of said conduits and of such formation that a 55 drop by drop filling of the container will eventually cause a syphonic flow of the water from the container through the outlet conduit.

DONALD F. ROSE. 60

ery of such flattened cross-section area is greater than a circle enclosing the same area and thus the surface tension will increase at this section of the conduit.

5 As water accumulates by dripping into the receptacle 17 it rises in the tube 23 and finally a drop completely fills the thinned or narrowed portion 25 and is held there by surface tension when a further drop causes a flow over into the 10 vertical tube 22, this action causing a suction and siphon action which removes all of the water from the container except a very small portion at the low point 20 causing water to be drawn rather voluminously out of the receptacle.

15 The volume collected at which this flushing takes place occurs at such intervals as to prevent the accumulation by deposit of any solid particles as might otherwise occur. In this manner before the absorbed odors have a chance to deposit 20 a slime upon the receptacle the water is discharged from the receptacle and as it is discharged in a substantial volume and not spread out along the pipes to evaporate, no deposit occurs along the pipes at any point.

25 If it is desired that the receptacle be placed below a refrigerator which is already in use rather than be built in, the receptacle similar in all respects to that described will be positioned as shown in Fig. 5, in which the legs of the refrigerator 30 will support the same spaced from the floor 31 and the conduit 22 will be positioned in the drain pipe 32 leading through the floor 31. The ice box drain 33 empties into the receptacle, there being already provided in boxes 35 of this character a seal to prevent the flow of air into the ice containing compartment.

It is found that flushing takes place in ordinary use about every hour and a half and for this short period no accumulation or settling of 40 the slime occurs, the same all being dissolved and there being insufficient evaporation of the accumulated water to cause any deposit.

The receptacle holds about a quart of water before flushing occurs and this being cold water 45 in the location shown in Fig. 1 assists in absorbing any heat from the ice box in compartment 11 whereby this cold water is utilized for assisting in cooling the refrigerator and thus boosts refrigeration in the cabinet.

50 An advantage for the use of the receptacle in the location shown in Fig. 5 beneath the refrigerator is also found. When in this location the body of water which collects warms up as it collects and upon the dropping of another drop 55 of cold water into the receptacle this water quickly disseminates into the warmer water and does not chill the metal receptacle 18 to such an extent as occurs where a lesser amount of water or no water is collected and the cold drop strikes 60 the metal receptacle. Thus, by reason of the
